RESTRAINING COLLAR DEVICE FOR SQUIBBING MISSILE MOTORS

Allan G. Barrett and Francis L. Albers, China Lake, Calif., assignors to the United States of America as represented by the Secretary of the Navy

Filed Apr. 23, 1970, Ser. No. 31,332

Int. Cl. G01m 17/00

U.S. Cl. 73—117.4

2 Claims

ABSTRACT OF THE DISCLOSURE

A device for restraining missile motors for squibbing. It comprises an alignment fixture and a restraining collar assembly mounted to a back plate whereby when a missile is moved into alignment the restraining collar assembly engages the missile hook or hanger on the outside of the motor casing thereby accurately positioning the missile so that current will flow. Only when accurately positioned will the missile motor be squibbed.

GOVERNMENT INTEREST

The invention described herein may be manufactured and used by or for the Government of the United States of America for governmental purposes without the payment of any royalties thereon or therefor.

BACKGROUND OF THE INVENTION

The present invention relates to a device for restraining missile motors during check-out.

In the missile field it has not been the practice to restrain a missile for squibbing. Heretofore missiles were laboriously loaded and unloaded for check-out. The present device provides a safe, reliable, and economical means for squibbing missile motors and avoids the delay occasioned by loading and unloading the missiles.

DESCRIPTION OF THE DRAWINGS

FIG. 1 shows in section a preferred embodiment of the invention with a missile motor in place;

FIG. 2 is a top view of the restraining collar assembly; and

FIG. 3 is a view of the clamp which engages the missile hook in accordance with this invention.

DESCRIPTION OF THE INVENTION

Referring now in detail to the drawing there is shown in FIG. 1 a missile 31 resting on a missile stand 19. Stand 19 comprises legs 20, a rail 22 supported on brackets 33 suitably affixed to the top of legs 20. A tray 26 for tools extends between legs 20 at a predetermined distance below and parallel with rail 22 being also affixed to brackets 33. Legs 20 are provided with castors 21 for ease in movement of missile stand 19. A series of rests 32 are secured along rail 22 for receiving the missile motor 31 likewise a plurality of safety straps 23 are attached along rail 22 for purposes of securing the missile motor 31 for check-out. At the rear of rail 22 there is provided a recess 34 for engagement with an alignment pin 11 which is attached to wall support beam 10. Wall support beam 10 is supported by a cement wall (not shown). Other means may be used to give the necessary support to said beam. A restraining collar assembly 14 is secured to beam 10 which restrains and aligns the missile motor 31 for squibbing. Assembly 14 on side view

2

resembles a right triangle. It comprises a vertical tubular steel cylinder 15 of predetermined length fitted over a solid steel post 12 which is affixed by braces 13 to wall support beam 10. Cylinder 15 is movable with relation to post 12. A release means 16 shown in position through aperture 35 is adapted to control the movement of cylinder 15. A bar member 17 positioned parallel to rail 22 is welded at its distal end to the base of cylinder 15. A knee brace 18 extends from the top of cylinder 15 to which it is welded to a predetermined point near the front end of bar 17 to which it is welded. Located near the end of bar 17 there is provided a clamp means shown at 30 for engaging the hook or hanger 28 of missile 31 as shown in detail in FIG. 3. Various types of clamps may be designed which are suitable for attachment to the missile. A switch 25 and switch cover 29 are mounted on the front end of bar 17 as shown in FIGS. 1 and 2. Assembly 14 is movable up and down and around post 12 whereby said assembly can be readily adjusted to engage the missile hook and thereby align the missile.

When it is desired to squib a missile motor, the missile is positioned on rests 32 and strapped to the missile stand 19 and moved to position against plate 10 where alignment pin 11 slides into recess 34 on the stand. Restraining collar assembly 14 is positioned so as to cause clamp means 30 to engage hook 28 on the missile. When the missile is accurately positioned, current will flow.

What is claimed is:

1. A restraining collar device for squibbing missile motors of the type provided with a hook positioned on the outside of the motor case comprising in combination with a missile alignment fixture a vertical support beam secured to a stationary wall; a solid post of predetermined size mounted parallel to said beam and affixed thereto; a cylinder positioned around said post and adapted to move with relation to said post; a bar of predetermined length affixed at its distal end to the base of said cylinder; a knee brace extending between the top of said cylinder and the front end of said bar and being affixed at predetermined points to the top of said cylinder and the front of said bar; a missile alignment fixture comprising a rail for receiving the missile positioned parallel to said bar and slidably engaged at its distal end to said vertical support for cooperating with said bar in aligning said missile; said bar being provided with a clamp means positioned near the front end of said bar for engaging and aligning said missile hook; and a switch means positioned on the front end of said bar adjacent said clamp adapted to be attached to said hook.
2. The device in accordance with claim 1 wherein a release means is provided on said post for controlling the movement of said cylinder.
